UNITED STATES PATENT OFFICE.

OSCAR B. HJORTH, OF SANDWICH, ILLINOIS.

SUBSTATION SELECTIVE APPARATUS.

1,072,459.

Specification of Letters Patent.

Patented Sept. 9, 1913.

Application filed July 18, 1912. Serial No. 710,147.

To all whom it may concern:

Be it known that I, OSCAR B. HJORTH, a resident of Sandwich, in the county of Dekalb and State of Illinois, have invented 5 certain new and useful Improvements in Substation Selective Apparatus, of which the following is a specification.

My invention relates to sub-station selective apparatus and particularly to apparatus 10 to be installed at each of a plurality of sub-stations to be selected for service from a central station and to have signaling mechanism at a selected sub-station controlled from the central station.

15 In prior selective systems complicated sub-station mechanism is required involving a great many contacts and depending for proper operation on time elements. Such time elements operate usually on very small 20 margin and the greatest of care must be taken in the control of the system. In fact, it is necessary for proper operation of such systems to provide accurately adjusted automatically operating central station selector 25 mechanism. If such central station apparatus becomes defective or inoperative the system is practically out of service as it is almost impossible to operate and control the system except with such carefully adjusted 30 and automatically operating central station mechanism.

One of the important objects of my invention is therefore to provide such construction and arrangement that all time elements 35 will be dispensed with and so that the system may readily be operated by means of ordinary keys and switches should the central station mechanism at any time become defective or inoperative.

40 Another object is to reduce sub-station contacts to a minimum, only one set of contacts being required at my improved sub-station apparatus to control the signaling circuit. In general the object is to provide 45 simplified construction and arrangement of sub-station apparatus having a minimum of contacts and being entirely devoid of time elements.

The various features of the invention will 50 be clearly understood by reference to the accompanying drawing in which—

Figure 1 is a plan view of a sub-station outfit, and Fig. 2 is a side elevational view showing more clearly the construction of the 55 step-up ratchet wheel mechanism.

The sub-station apparatus shown com-

prises a polarized main relay 5, a step-up electro-magnet 6, a signal controlling circuit relay 7, a releasing electro-magnet 8, a toothed selector wheel 9 which carries a contact arm 10 forming one terminal of a signaling circuit, and the step-up movement of this wheel is controlled by the step-up electro-magnet together with the spring 11. The armature 12 of the signaling circuit 60 controlling relay 7 controls the coöperation of the other terminal of the signaling circuit with the terminal contact 10, and this relay also controls the circuit for the release electro-magnet, which will be presently 65 described in detail.

The main relay controls the circuit for the other relays and electro-magnets, and as shown, comprises the winding spools 13, 13' mounted on the cores 14, 14' connected 70 at one end by the yoke 15. A non-magnetic frame 16 connects the pole ends of the cores, and mid-way between the pole ends this frame pivots an armature 17 which is polarized by the permanent magnet 18 extending 75 from the yoke 15. A contact extension or arm 19 at one end of the armature engages between the upper ends of light springs 20 and 21 extending upwardly from the bracket 22, these springs normally holding the armature 80 in neutral position with reference to the electro-magnet poles. At one side of the arm 19 the contact post 23 mounts a contact screw 24. At the opposite side of the arm 19 the post 25 supports the abutment screw 26. Extending from the other end of the armature is a contact arm 27 adjacent whose end is a post 28 carrying the contact screw 29. The various parts and 85 mechanisms of the sub-station apparatus are 90 mounted upon a suitable supporting plate or base 30. When the main relay is deenergized the springs 20 and 21 hold the armature in neutral position so that the arms 19 and 27 are disconnected from the contact 95 screws 24 and 29 and the abutment screw 26. Upon current flow of one polarity 100 through the electro-magnet windings the armature will be attracted to carry arm 19 into engagement with contact screw 105 24, and upon current flow of opposite polarity through the windings, the armature will swing in the opposite direction to carry arm 27 against the contact screw 29 and the arm 19 against abutment screw 26. Coöperation 110 of the armature structure with the contact 24 controls the circuit for the step-up

electro-magnet 6. The armature 31 of this electro-magnet is pivoted at its upper end to the yoke 32 and at its lower end is pivoted to the pawl arm 33 which co-operates with the teeth of the step-up ratchet wheel 9. The swing of the armature and the movement of the pawl arm is controllable by the adjustable abutment screws 34 and 35, and the adjustable abutment screw 36 limits the upward throw of the pawl arm. The armature 31 is normally held in retracted position by the abutment of the light spring extension 36' with the abutment screw 37.

The armature 38 of the release electro-magnet 8 carries spring extension 39 for co-operating with the ratchet wheel 9 as a detent therefor. This detent spring engages with the wheel below the pawl arm 33 and when the armature 38 is attracted the ends 20 of the detent and pawl arm will be raised to release the ratchet wheel after a setting thereof. The ratchet wheel has a long tooth 40 which is normally engaged by the detent and the pawl arm and at such time the ratchet wheel will not be released even though the armature of the releasing electro-magnet is attracted as the abutment screw 36 prevents upward movement of the end of the pawl arm beyond the long tooth. 25 The armature 38 is normally held in retracted position by the engagement of its spring extension 41 with the abutment 42. Co-operation of the contact 29 and the armature structure of the main relay controls the circuit for the signaling circuit controlling relay 7. The armature 12 of this relay carries a contact spring 43 which forms one terminal of the signaling circuit and this contact co-operates with the contact arm 10 30 on the ratchet wheel 9 to control the signaling circuit, as will be described later. The armature structure 12 also carries another spring 44 forming one terminal of the circuit for the release electro-magnet, the other 35 terminal of this circuit being the contact screw 45. Extending from the armature structure 12 and parallel with the contact spring 43 is the arm 46 whose end 47 extends downwardly to form the locking hook 40 or abutment for the contact arm 10, this end 47 extending a distance below the adjacent end of the contact spring 43. Below the contact spring 43 and parallel therewith is arm 48 which carries the insulating stud 49 45 received by suitable opening in the contact spring 43, so that this spring may freely vibrate but is prevented from becoming laterally displaced. The armature structure 12 is normally held in retracted position by 50 the spring extension 49' engaging the abutment 50 and during such retracted position the arms 48 and 46 and contact spring 43 are out of the path of contact arm 10, and the contact extension 44 is disconnected from 55 terminal 45.

Fig. 2 shows more clearly the construction of the selector ratchet wheel and contact mechanism. The wheel 9 is mounted on the spindle 51 pivoted in the ends of the bracket 52, the spiral restoring spring 11 connecting at one end to this spindle and its outer end being secured to the post 53. Nuts 54 and 55 on the spindle clamp between the disk 56 from which the contact arm 10 extends.

On the supporting base binding posts *a*, *b*, *c*, *d*, and *e* are mounted; the post *e* being electrically connected with the supporting base 30 which in this case is of conducting material, while the other binding posts are insulated from the base. Contact supporting posts 23 and 28 are also insulated from the base, and the contact post 45 and the bracket 52 are electrically connected with the base. Binding posts *c* and *d* are connected by conductors *f* and *g* with the terminals of the main relay 5. One terminal of the step-up electro-magnet is connected through conductor *h* with the binding post *a* and the other terminal of this electro-magnet is connected through conductor *i* with the contact 24. Binding post *a* also connects through conductor *j* with one terminal of the relay 7 whose other terminal is connected through the conductor *k* with the contact 29. Binding post *b* is connected by conductor *l* with the contact spring 43. One terminal of the electro-magnet 8 connects with conductor *h* and thus with binding post *a*, while its other terminal is connected by conductor *m* with contact spring 44. A local source of current *n* connects with binding posts *a* and *e* and a signaling device *o* such as a bell is connected with binding posts *a* and *b*. The line conductors *L*, *L'* extend from binding posts *c* and *d* to the central station *C*. At the central station suitable means may be provided for sending either positive or negative current impulses over the line. As shown, the current *S* is provided at the central station and its connection with the line is controlled by a key *p*, a suitable pole changer switch *q* being interposed so that upon actuation of the key the direction of current flow through the line will be in one direction or the other.

Describing now the operation, suppose it is desired to select for service the sub-station shown. The selection number of the sub-station shown is 30, that is, it will take thirty attractions of armature 31 to carry the contact arm 10 from its normal position to the signaling position. The central station operator after properly adjusting the pole changer *q* will actuate the key *p* thirty times. Upon each such actuation current will flow from the positive pole of the battery *S* through the pole changer and line conductor *L'* to binding post *d* thence through the windings of the relay 5 to binding post *c*, and through line conductor *L* and the pole 130

changer to the negative terminal of the battery. Upon each impulse, contact 24 will be engaged by the arm 19 of the armature structure, which armature structure is electrically connected with the base 30. Each such engagement with the contact 24 will close the circuit of the step-up electro-magnet to cause one step-up actuation of the armature 31 and pawl arm 33. The step-up circuit includes battery *n*, binding post *a*, conductor *h*, the step-up electro-magnet winding, conductor *i*, contact 24, the armature structure, and binding post *e*. After the ratchet wheel 9 has been advanced thirty teeth, the end of contact arm 10 will be below the end of spring 43 and between the end of arm 48 and the hook 47. After such setting up of the contact arm 10 the pole changer *q* is reversed and the key *p* depressed to close the circuit and current will flow from the positive pole of battery *S* through the pole changer and line conductor *L'* to binding post *c*, and in reverse direction through the windings of relay 5 and back to the battery. The armature 17 will then be swung to engage its arm 27 with contact 29 to close the following circuit through the signaling circuit controlling relay 7: battery *n*, binding post *a*, conductor *j*, winding of relay 7, conductor *k*, contact 29, arm 27 and armature structure 17, base 30, and binding post *e*. Relay 7 being energized will attract its armature to carry the end of spring 43 toward the end of contact arm 10 and upon engagement of these contacts the following signaling circuit will be closed: battery *n*, signaling device *o*, binding post *b*, conductor *l*, contact spring 43, contact arm 10, base 30 and binding post *e*. The signaling device *o* which may be a call bell, will thus respond.

When the armature 12 is fully attracted contact extension 44 thereon will engage with contact 45 to close the following circuit: battery *n*, binding post *a*, conductor *h*, the winding of the electro-magnet 8, conductor *m*, contact extension 44, contact 45, base 30, and binding post *e*. The adjustment, however, is such that before contact extension 44 reaches contact 45 the end of locking hook 47 will have passed below the upper end of contact arm 10. This arm will be held to close the signaling circuit so long as relay 7 is energized, even after the releasing circuit is closed and the detent 39 and pawl arm 33 raised from the wheel 9. The signaling circuit can be kept closed any length of time by the key *p* at the central station and immediately upon opening of this key both the relay 7 and the electro-magnet 8 become deenergized and their armatures will retract, detent 39 dropping into engagement with the ratchet wheel 9 to lock the arm 10 in position just outside of the hook 47. To finally restore the step-up wheel, another negative impulse is sent through the main relay by actu-

ation of key *p* to again energize electro-magnets 7 and 8. The attraction of the armature structure 12 will not affect the contact arm 10, as the arm is out of range thereof, but upon attraction of armature 38, the detent 39 and pawl arm 33 will be raised from the ratchet wheel and this wheel restored to normal position by the spring 11 and with its long tooth 40 in engagement with detent 39 and pawl lever 33. The substation mechanisms are thus again restored to normal position ready for another selection and signaling operation. As the station operator may neglect to give the final negative impulse to fully restore the ratchet wheel, the safe procedure would be to send a negative impulse through the main relay to cause the released electro-magnet to allow restoration of the ratchet wheel if it is not already in such normal position. Where automatic selector mechanism is employed at the central station, such primary restoring impulse can be taken care of by such apparatus to be sure that all parts are in normal position before the operation of selection is begun.

At the various sub-stations connected with the line the contact arms 10 are of course differently set. When the selection has been made of sub-station 30, the contact arms at sub-stations 1 to 29 will be at the left of and below the end of the arms 48 on armature structures 12, these arms 48 having no electrical connection with the signaling circuit. Now when the ringing relays 7 at all the sub-stations are energized by the reverse current flow through the main relay, the signaling circuit at sub-station 30 only will be closed and the contact arm at this sub-station locked against retraction by the hook 47. When now the contacts 44 and 45 are closed by relays 7 the releasing electro-magnets at the various sub-stations will be energized and the detent pawls withdrawn from the step-up wheels. However, such release of the pawls will not allow the step-up wheels to return to normal as the wheel at station 30 is held by the hook 47 and at the other stations the wheels are held by the engagement of the contact arms 10 with the arms 48 on the attracted armature structures 12. So long as the circuit is retained through the relays 7 the signal circuit at station 30 will remain closed and the signal bell sounded and as soon as the energizing circuit is opened both ringing and releasing relays will be deenergized, the armature structures 12 being released from the contact arms 10 and the detent pawls dropping toward the step-up wheels and before such step-up wheels are caught by the pawls they will have returned at least partly to normal position. Another negative impulse then through the main relay will effect energiza-

tion of the ringing and detent relays and the pawls will be raised until all the step-up wheels have been fully restored.

My improved construction and arrangement of sub-station apparatus is extremely simple as there are no time elements to be considered and only a few contacts are necessary, the signaling circuit of each sub-station being controlled by a single set of contacts. The signaling circuit is absolutely controllable from the central station as after a selection operation under current flow of one polarity through the main relay ringing will not take place until current of reverse polarity is sent through the line and main relay and the signaling circuit will be kept closed so long as such reverse current flow is maintained.

As changes and modifications will no doubt be possible I do not desire to be limited to the precise construction and arrangement shown and described, and

I therefore claim the following:

1. In sub-station selective apparatus, the combination of a movable contact member, electro-magnet mechanism associated with said contact member and adapted to effect step by step set-up movement thereof, an electro-magnet having an armature structure provided with a contact adapted upon attraction of said armature structure to engage with the set-up movable contact member, a signaling circuit closed by said engaging contact members, detent mechanism for holding said movable contact member in set-up position after setting up thereof by said electro-magnet mechanism, a retaining member on said armature structure moved upon attraction of said armature structure to prevent restoration of said movable contact member independently of said detent mechanism, a releasing electro-magnet for controlling said detent mechanism, and a circuit for said releasing electro-magnet closed by said armature structure during the latter part of its movement whereby said set-up contact member is locked by the retaining member before release of the detent mechanism.

2. In sub-station selective apparatus, the combination of a movable contact member, electro-magnet mechanism for effecting step by step setting up movement of said contact member, detent mechanism for preventing return of said contact member after setting up thereof, a releasing electro-magnet for said detent mechanism, a signaling electro-magnet having an armature structure provided with a contact adapted upon attraction of said armature structure to engage with the movable contact member, a signal circuit closed by said contact members, a retaining member on said armature structure moved by the attracted armature structure to retain said movable contact

member against restoration independently of said detent mechanism, an energizing circuit, said electro-magnets being connected with said energizing circuit in bridge of each other, and contact mechanism controlled during the latter part of movement of the signaling electro-magnet armature structure for closing the energizing branch of said releasing electro-magnet whereby said detent mechanism will not be actuated until said retaining member has become effective.

3. In sub-station selective mechanism, the combination of a step-by-step movable contact member, electro-magnet mechanism for controlling the step by step setting up movement of said contact member, detent mechanism for said setting up member, a releasing electro-magnet controlling said detent mechanism, a signaling electro-magnet having an armature structure provided with a contact adapted upon attraction of said armature structure to engage with the contact member, a signaling circuit closed by the engaged contacts, a controlling circuit for said signaling electro-magnet, contact mechanism closed during the latter part of movement of said armature structure, and a circuit for said releasing electro-magnet controlled by said contact mechanism whereby said detent mechanism will be actuated to release the movable contact member a period of time after engagement of said contact members to close the signaling circuit.

4. In sub-station selective mechanism, the combination of a main relay mechanism, a signaling circuit, a contact for said signaling circuit, a relay controlling said contact and having a circuit controlled by said main relay, a movable contact for said signaling circuit, electro-magnetic step-up mechanism for shifting said movable contact into the path of said first mentioned contact whereby upon actuation of said second mentioned relay said contacts will be brought into engagement and said signaling circuit closed, and electro-magnetic restoring mechanism for releasing said movable contact and having a circuit controlled by said second mentioned relay.

5. In sub-station selective mechanism, the combination of a polarized main relay, a signaling circuit, a controlling relay for said signaling circuit carrying a contact therefor, a step-up member carrying another contact for said signaling circuit, a step-up electro-magnet having an armature associated with said step-up member to effect movement of said step-up member to carry its contact into the path of said other contact whereby said signaling circuit may be closed upon actuation of said signaling circuit controlling relay, a releasing circuit controlled by said signal circuit controlling relay, an electro-magnet in said releasing circuit, and an ar-

5 mature for said releasing electro-magnet having detent engagement with said step-up member to lock said member after movement thereof by said step-up electro-magnet, 5 said armature when attracted causing release of said step-up member from the locking 70 detent and step-up armature.

6. In sub-station selective mechanism, the 10 combination of a polarized main relay, a signaling circuit, a controlling relay for said signaling circuit having its own circuit controlled upon current flow in one direction through said main relay, the armature structure of said controlling relay carrying a contact forming one contact of said signaling 15 circuit, a step-up wheel having a contact and adapted to carry said contact into the path of said controlling relay contact, a step-up electro-magnet having an armature structure coöperating with said step-up wheel to effect step-by step movement thereof, a circuit for said step-up electro-magnet controlled upon current flow through said main relay in the opposite direction, a releasing 20 electro-magnet having an armature, a detent extension on said armature coöperating with said step-up wheel to lock said wheel after actuation thereof, attraction of said releasing electro-magnet armature causing said 25 detent extension and said step-up electro-magnet armature structure to be released from said step-up wheel, a spring for returning said step-up wheel to normal position after such release, and a circuit for said 30 releasing electro-magnet controlled by said signaling circuit controlling relay.

7. In sub-station selective apparatus, the 40 combination of a polarized main relay, a signaling circuit, a controlling relay for said circuit, a contact carried by the armature of said controlling relay and forming one terminal of said signaling circuit, a contact arm, step-up mechanism for effecting step by step movement of said arm toward the path of said controlling relay contact, said arm forming another terminal of the signaling circuit to close said signaling 45 circuit upon engagement thereof by the controlling relay contact, detent means for locking said arm against return movement before said arm is engaged by said contact, additional detent means for locking said arm against return movement after engagement thereof by said contact, and electro- 50 magnetic means for causing said first mentioned detent means to release said arm after release thereof by said additional detent means.

8. In sub-station selective apparatus, the 60 combination of a selector member carrying a contact, a signaling circuit of which said contact forms one terminal, a controlling relay for said circuit, a contact controlled by said relay to be brought into engagement 65 with said movable contact after adjustment

of said movable contact, an electro-magnet for effecting step-by step movement of the selector member, a releasing electro-magnet for effecting release of said selector member, a circuit for said releasing electro-magnet controlled by said controlling relay, locking means controlled by said controlling relay for locking said contacts against disengagement when said releasing electro-magnet is primarily energized, a circuit for 70 said controlling relay and electro-magnetic switch mechanism for controlling said circuit.

9. In sub-station selective mechanism, the combination of a signaling circuit, a rotatable arm forming one terminal of said circuit, a controlling relay for said circuit having an armature structure provided with a contact forming the other terminal of said circuit, attraction of said armature structure when said contact arm has been moved to a certain position causing engagement of said arm and said armature contact to close the signaling circuit, a ratchet wheel connected with said contact arm, a step-up electro-magnet, a pawl lever controlled by said electro-magnet to effect step by step rotation of said ratchet wheel and thereby step by step rotation of the arm toward the path of said controlling relay contact, a releasing 80 electro-magnet having an armature structure, a detent extension on said armature structure for coöperating with said ratchet wheel to lock said wheel in adjusted position after each advancement thereof, a circuit for said releasing electro-magnet closed upon attraction of said circuit controlling relay, energization of said releasing electro-magnet serving to disengage said detent extension and said pawl from said ratchet 85 wheel, and a locking arm on the armature structure of said controlling relay for locking said contact arm against retraction before closure of the releasing circuit by said controlling relay.

10. In sub-station selective mechanism, the combination of a signaling circuit, a ratchet wheel having a contact arm forming one terminal of said circuit, a controlling relay for said circuit having an armature structure, a contact carried by said armature structure adapted upon attraction of said armature structure to engage with said contact arm after said contact arm has been moved into the path of said armature contact, a step-up electro-magnet having an armature structure, a pawl lever connected with said armature structure and coöperating with said ratchet wheel to effect step by step movement of said ratchet wheel contact arm toward said controlling relay armature contact, a releasing electro-magnet having an armature structure, a detent extension on said releasing armature structure engaging with said ratchet wheel below said pawl le- 110 115 120 125 130

ver to lock said ratchet wheel against retraction after each advancement thereof by said pawl lever, a circuit for said releasing electro-magnet, circuit closing mechanism controlled by said controlling relay for said releasing circuit, said circuit closing mechanism being closed only after said controlling relay armature approaches the end of its movement, a locking arm on the controlling relay armature structure for preventing re-

tractive movement of said contact arm when said releasing circuit is closed, and a main relay for controlling the circuits of said controlling relay and said step-up relay.

In witness whereof, I hereunto subscribe 15 my name, this 15th day of July, A. D., 1912.

OSCAR B. HJORTH.
